TION OF CONNECTICUT.

CURTAIN-ROD FIXTURE.

1,186,895.

Specification of Letters Patent. Patented June 13, 1916.

Application filed August 8, 1914. Serial No. 855,742.

To all whom it may concern:

Be it known that we, WILLIAM H. EDSALL and FRANK LA OTIS LATHROP, citizens of the United States, residing at Wallingford, 5 New Haven county, State of Connecticut, have invented certain new and useful Improvements in Curtain-Rod Fixtures, of which the following is a full, clear, and exact description.

This invention relates to curtain rod fixtures and is designed to provide a simple form of curtain rod and bracket support which may be used both as an "inside" and "outside" fixture. In addition to affording 10 this result, our invention provides a simple and inexpensive structure for attaining this result.

It is described in detail in the following specification, taken in connection with the 15 accompanying drawings, in which,—

Figure 1 is a fragmentary view in elevation, showing the curtain rod fixture applied to a window casing and used as an "outside" fixture; Fig. 2 is a view in front elevation, 20 showing the invention used as an "inside" fixture; Fig. 3 is a vertical sectional view through the rod supporting bracket of the fixture; Fig. 4 is a view in elevation of said bracket; Fig. 5 is a detail perspective view 25 of the socket member of the bracket.

Referring to the drawings by numerals, 1 designates a window sash, and 2 a window casing, to the outer face of which the rod supporting brackets are attached when the 30 device is used as an "outside" fixture. When used as an "inside" fixture the brackets will be attached to the inner edge 2^a of the window casing, as seen in Fig. 2 of the drawings.

3 designates the curtain rod having its opposite ends provided with knobs or heads 4, 40 preferably spherical, providing adjacent the knob ends an annular groove 4^a forming a relatively reduced neck. This rod 3 may be, and preferably is, of the usual telescoping 45 type, so that the curtain or other hanging may be readily mounted thereon. The ends of these rods are supported by and detachably mounted in a bracket member of a peculiarly advantageous construction. This 50 bracket member comprises a base plate 5 arranged to be secured to the sash by suitable means, as the screws shown, the base plate intermediate its ends being prefer- 55 ably expanded as in 5^a and formed with a

seat 7, preferably centrally of the plate, this seat being offset from the body of the base plate as indicated at 6 (Figs. 2 and 3). Mounted on this seat 7 and swiveled thereto is a socket member designed to receive the 60 knob end of the curtain rod. This socket member is formed of a tubular cup portion 8 having its sides expanded laterally outward to form a spherical socket, the sides being slotted to provide segmental spring 65 fingers 9, one side being cut away, as at 10, to provide a lateral clearance notch or opening in which the neck of the rod adjacent the knob may lie when the fixture is used in certain positions, for example, as an "out- 70 side" fixture. This is most clearly illustrated in Fig. 1 of the drawings. The socket member is swiveled upon the seat 7 by suitable means, such as the rivet pin 11, whose outer end is offset against the outer face of 75 the base of the cylindrical portion. Referring particularly to this fixture, it will be seen that the knob end 4 is inserted directly into the spherical socket portion, its periphery engaging the spring finger segments 9 80 of the socket which will snap thereover when the knob is forced therebetween. The side of the rod adjacent this knob extends laterally from the socket through this notch 10. These spring fingers will, of course, be 85 curved on an arc substantially coincident with the arc of the spherical knob 4, and will extend beyond the median line of the sphere, inasmuch as they themselves form a socket greater than a hemisphere. These 90 spring fingers, therefore, will extend beyond the center or median line of the rod and knob end so as to securely hold the rod within the socket. The width of the notch 10 will also be less than the diameter of the spherical 95 knob 4, so that as the spring fingers form a socket greater than a hemisphere, the rod may not be withdrawn from the socket by longitudinal movement.

When the fixture is used as an "inside" 100 bracket, it will be applied to the inner edge 2^a of the casing, as best seen in Fig. 2 of the drawings. In such an event the swiveled socket will preferably be turned to present the notch 10 uppermost, so that the knob end 4 may be seated within the socket by longitudinal bodily movement of the rod axially of the socket, the knob expanding the 105 spring fingers 9, which will snap thereover and will extend to a point beyond the me- 110

dian line of the spherical end, holding the rod against accidental withdrawal from the socket by longitudinal movement. The rod end is also retained in its socket against 5 lateral movement therefrom because the entrance notch 10 is of less width than the diameter of the spherical knob.

From the foregoing it will be seen that by 10 providing a swiveled socket piece of the character described the bracket may be utilized both as an "inside" and "outside" fixture, and is so constructed as to retain the rod against accidental withdrawal through either longitudinal or lateral movement 15 thereof. From the foregoing it is also obvious that the socket is so constructed as to afford a maximum grip on the head of the rod while still permitting of a universal adjustment of the rod relatively to the bracket. 20 While a specific embodiment of rod and bracket support have been illustrated and described herein, it will be obvious that our invention is not limited to this specific structure, but that the invention is susceptible of 25 variation in structure and in relative arrangement of parts within the spirit of the invention and scope of the appended claims.

What we claim, therefore, and desire to 30 secure by Letters Patent is,—

- 30 1. In a device of the character described, a curtain rod having an end knob member, and a bracket arranged to be supported from a window or other casing, and including a swiveled socket member for said knob member, one side of said member being cut away 35 to present a notch of a width less than the width of the knob member, one of said members being yielding relatively to the other member.
- 40 2. In a device of the character described, a curtain rod having an end knob, and a bracket arranged to be supported from a window or other casing, and including a swiveled socket member for said knob end 45 having resilient sides, said member at one

side providing a notch of less width than the greatest width of said knob end.

3. In a device of the character described, a curtain rod having a substantially spherical end knob, and a bracket arranged to be 50 supported from a window or other casing, and including a swiveled cup member provided with a plurality of spring fingers of a curvature to provide a socket greater than a hemisphere for said spherical knob, one 55 side of said socket being cut away to provide a notch of less width than the diameter of said spherical knob.

4. In a device of the character described, a curtain rod having a substantially spherical 60 end knob, and a bracket arranged to be supported from a window or other casing, and including a swiveled cupped member having spring fingers curved substantially on the arc of said spherical knob, and providing a socket greater than a hemisphere, one side of said socket being cut away to 65 provide a notch of a width less than the diameter of said spherical knob.

5. In a device of the character described, 70 a curtain rod, and a bracket arranged to be supported from a window or other casing, and including a swiveled socket member for the end of said rod, said member having an axial socket opening and having one side 75 only formed with a clearance notch.

6. In a device of the character described, a curtain rod, a bracket, an outwardly opening resilient socket swiveled at its base to said bracket, a head on said rod connected 80 thereto by a relatively reduced neck, said socket having a clearance recess at one side of smaller dimensions than said head and larger dimensions than said neck.
